2 SHEETS—SHEET 2

FIG. 4: A top-down view of a device assembly. It features a central vertical column with a circular opening. Above this column are two sets of components: on the left, a vertical slot 43 with a downward-pointing arrow, a vertical slot 34, a vertical slot 37, and a horizontal slot 5; on the right, a vertical slot 43 with a downward-pointing arrow, a vertical slot 34, a vertical slot 37, and a horizontal slot 5. Below the central column are four vertical slots, each containing a circular component labeled 36. The labels 5 and 5' are placed near the bottom of the central column, and the label 11 is placed near the bottom of the central column. The labels 35 are placed at the bottom of the vertical slots.

FIG. 5: A side view of the device assembly. It shows a base 42 with a stepped profile. On top of the base is a vertical structure 44. The labels 36 and 37 are placed near the bottom of the vertical structure 44. The label 41 is placed near the top of the vertical structure 44.

Application August 19, 1948, Serial No. 45,183

9 Claims. (Cl. 34—157)

1

This invention relates to apparatus for the treatment of textile fabrics. More particularly the invention relates to apparatus for shrinking, or for drying and shrinking, textile fabrics. The preferred form of the apparatus, hereinafter described, serves both to shrink and dry moist fabric material as it comes from the various processes to which it is subjected in the normal course of treatment. While the invention is applicable generally to textile fabrics, it is particularly applicable to the shrinking and drying of tubular knitted fabrics which undergo a great deal of stretching in the course of manufacture and subsequent treatment, including dyeing and bleaching.

The problem of garment shrinkage has plagued the textile industry for many years, particularly the underwear industry wherein shrinkage has been extremely severe due to the character of the material and the relatively great stretch imparted to it in processing. The prevention of garment shrinkage requires that the material be shrunk to remove the "stretch" prior to the manufacture of garments from the material. Recent developments have shown that relaxation of the material for a period of time, especially during drying, tends to cause the constituent fibres to be restored to their normal tensionless condition, and thereby removes the stretch previously imparted to the fibres and renders the fabric material substantially immune to later shrinkage. As heretofore practiced, however, such relaxation shrinkage has involved the use of costly apparatus comprising a plurality of conveyors which serve to support the material. Such an apparatus may comprise as many as five conveyors in superposed relation, by which the fabric is conveyed, in succession, during the shrinking and drying treatment. The cost of such an apparatus tends to prohibit its commercial use.

Loop driers have long been used in the textile industry, in which driers the fabric is suspended in successive loops on a moving carrier and air is brought into contact with the loops to dry the fabric. While such driers avoid the use of a plurality of conveyors, they are generally unsatisfactory in that the suspension of the loops subjects the fibres to tension and imparts further stretch thereto, and furthermore the air tends to disarrange the loops causing some to become extremely short and others to become extremely long. Consequently loop driers, when used, have only aggravated the shrinkage problem, and they have not been wholly satisfactory even from the standpoint of drying alone.

2

The principal object of the present invention is to provide a commercially suitable apparatus for relaxation shrinkage, and also for drying, of textile fabrics.

5 The present invention is based on the novel concept of arranging a fabric in successive loops and providing basket supports for the loops so as to eliminate tension therein and to completely relax the fibres, and subjecting the supported loops to the drying influence of air or any other gaseous medium. By providing a conveyor arrangement for thus supporting the fabric in successive loops, it is possible greatly to simplify and to reduce the cost of shrinking and drying apparatus.

15 According to the preferred form of the invention, there is provided an apparatus comprising a gasket conveyor having successive basket loops in which the fabric is loosely carried, and the apparatus also preferably comprises air jets arranged to dry the fabric while it is completely relaxed on said conveyor. By virtue of the form of the conveyor, it is equivalent in length to a plurality of flat conveyors, as regards treatment of the fabric, and a single conveyor suffices for the complete shrinking and drying treatment. Moreover, the apparatus is of simple construction and may be manufactured at considerably lower cost than a multiple conveyor apparatus.

20 The invention may be clearly understood from the following detailed description with reference to the accompanying drawings, wherein

Fig. 1 is a diagrammatic plan view of an apparatus constructed according to the invention;

Fig. 2 is a diagrammatic side elevational view of the same, with a portion of the casing broken away and shown in section to disclose the interior mechanism;

Fig. 3 is a cross sectional view taken along line 3—3 of Fig. 2;

Fig. 4 is a relatively large scale sectional view taken longitudinally through a portion of the basket conveyor and showing several of the basket loops thereof; and

Fig. 5 is a fragmentary sectional view taken along line 5—5 of Fig. 4.

45 Referring first to Figs. 1 and 2, the apparatus comprises an elongate housing 10 of suitable dimensions through which the basket conveyor 11 extends longitudinally. The housing 10 may comprise a suitable framework (not shown) and a plurality of sheet metal sections numbered 12 to 17. As shown in Fig. 3, the metal sections are preferably covered with heat insulating material. Associated with said sections are 50 motor-driven fan units numbered 18 to 23, which

serve to circulate the air in each section, as hereinafter described.

The conveyor 11 is preferably of endless form and engages rotatable sprockets 24 and 25 at the opposite ends of the housing 10 external thereto. In the form of the apparatus illustrated, the sprockets 25 are driven by a motor-driven pulley 26 through the medium of a driving belt 27.

The fabric material F is supplied to the conveyor 11 at the left hand end thereof, as viewed in Figs. 1 and 2, by means of power-driven feed rolls 28 and 29. The latter are operated at a speed of rotation such that the fabric is fed to the conveyor at a rate sufficiently greater than the speed of the conveyor to enable disposition of the fabric loosely in the basket loops of the conveyor, with the fabric extending substantially the full depth of each basket loop, as hereinafter more fully described. This disposition of the fabric is effected by means of a transverse air nozzle 30 which extends the full width of the conveyor, and which is arranged at the feed end of the conveyor so as to blow the fabric into the successive basket loops of the conveyor. Pressurized air may be supplied to nozzle 30 from any suitable source. At the discharge end of the conveyor, the fabric material is fed to an inclined belt conveyor 31 which deposits the material on a scay 32. The conveyor 31 may be driven from the shaft of pulley 26 by means of a belt 33.

Referring now to Figs. 3 to 5, the basket conveyor 11 may comprise roller chains at each side carrying spaced transverse rods 34 which serve to support the basket loops 35. One of the roller chains is shown in Fig. 4 and comprises links 36 and rollers 37. In Fig. 3, two of the opposite rollers are visible at 38. Angle members 39 and 40 provide track surfaces along which the rollers run, said members being supported by the framework (not shown). As may be seen in Fig. 1, the sprockets 24 and 25 support the roller chains at the opposite ends of the housing 10.

The basket loops of the conveyor, which are preferably about nine inches deep, may be formed of suitable wire screen, as shown in Fig. 5. The screen member forming each basket loop may have its end portions looped about the rods 34 for free pivotal support thereby.

As shown in Fig. 3, within each section of housing 10 there is an air head 41 above the upper conveyor run and an air head 42 below said run. The upper air head 41 has a series of transverse downwardly directed nozzles 43, while the lower air head 42 has a series of upwardly directed transverse nozzles 44. The nozzles extend the full width of the conveyor. The upper and lower nozzles are preferably arranged in staggered relation, as shown in Fig. 4. The two air heads 41 and 42 are supplied with air from a common air duct 45 through air conduits 46 and 47. The air is supplied to said heads under pressure by the fan 48 of the associated motor-driven fan unit. Surrounding the conveyor and said air heads, and extending the full length of the housing 10, is an enclosure formed by wall members 49 and 50 having depending flanges 51 and 52 which form an outlet from said enclosure to the bottom of the casing 10. After ejection from the nozzles 43 and 44, the air is drawn downward through a filter 53 and about heating pipes 54 by the suction of fans 48. As may be seen in Fig. 2, the filter 53 and the heating pipes 54 extend the full length of the housing 10. The pipes 54 may carry steam or any other suitable heating agent.

In operation of the apparatus, the fabric is

loosely deposited in the basket loops, as shown in Fig. 4, so that it is completely free of tension. This is accomplished by feeding the fabric at a sufficient rate and by the blowing thereof into the basket loops by the air from nozzle 30. As the fabric is carried through the housing 10 by the basket conveyor, it is subjected to the heated air from nozzles 43 and 44 and is thus dried.

Since the apparatus effectively shrinks the fabric material and reduces its length by an amount comparable to the stretch previously imparted to it, the fabric must be sufficiently loose in the basket conveyor to permit such shortening of its length. Moreover, the fabric should preferably be sufficiently loose so that it may always extend the full depth of each basket loop in order that there will not be any tension on any of the fabric loops due to unsupported weight. Generally speaking, the stretch imparted to a fabric by processing and prior to drying thereof is about fifteen percent of its length at that time. Therefore, the fabric should be supplied to the conveyor at a rate such that the length of the fabric supported by the conveyor is about fifteen percent in excess of the effective conveyor length supporting the fabric.

While the invention contemplates any suitable depth of the basket loops of the conveyor, it is thought to be desirable to maintain the loops fairly short, e. g. about nine inches in depth.

The velocity of the air impinging on the supported fabric should not be sufficient to blow it out of the conveyor loops. As shown in Fig. 3, the relative amounts of air supplied to the upper and lower air heads may be regulated by means of an adjustable vane or deflector 55 in each of the ducts 45. These vanes may be mounted on a common shaft 56 extending the length of the casing and having an operating handle 57 externally of the casing.

It should be understood that the main and essential feature of the present invention is the support of the fabric in successive loops substantially free of tension so that the fibres are relaxed and are free to return to their normal tensionless condition. The promotion of drying of the fabric while thus relaxed may be carried out in any suitable manner by any suitable medium, although the use of upper and lower heated air jets has been found to be most efficacious in effecting rapid drying.

It will be understood, therefore, that the invention is not limited to the specific apparatus illustrated and described, but contemplates such other specific forms as may be found useful in the accomplishment of the desired results.

I claim:

1. In an apparatus for relaxed drying of textile fabrics, a conveyor comprising successive basket loops of foraminous material movable through a horizontal run, said basket loops being of relatively narrow loop width and of substantially greater loop depth, means for driving said conveyor at a predetermined speed, means for feeding the fabric to the conveyor at one end of said run at a rate sufficiently greater than the speed of said conveyor to enable deposition of the fabric loosely in said basket loops, air jet means arranged at the feed end of said conveyor run to effect the aforementioned deposition of the fabric, whereby the fabric is carried by the conveyor in a series of loops devoid of tension, and means for impinging air on the looped fabric as it is carried through said horizontal run.
2. In an apparatus for relaxed drying of textile

fabrics; a conveyor comprising an endless carrier and successive basket loops of foraminous material carried by said carrier; said conveyor being movable through a horizontal run, said basket loops being of relatively narrow loop width and of substantially greater loop depth, means for driving said conveyor at a predetermined speed, means for feeding the fabric to the conveyor at one end of said run at a rate sufficiently greater than the speed of said conveyor to enable deposition of the fabric loosely in said basket loops; air jet means arranged at the feed end of said conveyor run to effect the aforementioned deposition of the fabric, whereby the fabric is carried by the conveyor in a series of loops devoid of tension, and means for impinging air on the looped fabric as it is carried through said horizontal run.

3. In an apparatus for drying and shrinking moist fabric, an elongate housing, an endless conveyor extending longitudinally through said housing so as to provide a horizontal run of the conveyor through the housing to carry fabric therethrough, said conveyor comprising an endless carrier and successive basket loops of foraminous material carried by said carrier, said basket loops being of relatively narrow loop width and of substantially greater loop depth, means for driving said conveyor at a predetermined speed, means for feeding the moist fabric to the conveyor at the intake end of said housing at a rate sufficiently greater than the speed of said conveyor to enable deposition of the fabric loosely in said basket loops, an air nozzle extending transversely of said conveyor at the feed end thereof and arranged to effect the aforementioned deposition of the fabric, whereby the fabric is carried through said housing in a series of loops devoid of tension, and means for impinging heated air on the looped fabric as it is carried through said housing.

4. In an apparatus for drying and shrinking moist fabric, an elongate housing, an endless conveyor extending longitudinally through said housing so as to provide a horizontal run of the conveyor through the housing to carry fabric therethrough, said conveyor comprising an endless carrier and successive basket loops of foraminous material carried by said carrier, said basket loops being of relatively narrow loop width and of substantially greater loop depth, means for driving said conveyor at a predetermined speed, means for feeding the moist fabric to the conveyor at the intake end of said housing at a rate sufficiently greater than the speed of said conveyor to enable deposition of the fabric loosely in said basket loops, an air nozzle extending transversely of said conveyor at the feed end thereof and arranged to effect the aforementioned deposition of the fabric, whereby the fabric is carried through said housing in a series of loops devoid of tension, longitudinally spaced air nozzles in said housing above and below said horizontal run of the conveyor for impinging air on the looped fabric as it is carried through the housing, said last-mentioned air nozzles extending substantially the full width of said conveyor, and means for supplying heated air to said last-mentioned nozzles.

5. In an apparatus for drying and shrinking textile fabric, a conveyor including successive basket loops of foraminous material movable through a horizontal run, said basket loops being of relatively narrow loop width and of substantially greater loop depth, means for driving

said conveyor at a predetermined speed, means for feeding the fabric to the conveyor at one end of said run at a rate sufficiently greater than the speed of said conveyor that the fabric is loosely deposited in the basket loops with excess of the fabric at least approximately equal to the expected lengthwise shrinkage of the fabric, so that the fabric may shrink and still be supported by the basket loops, and means for promoting drying of the fabric as it is carried through said horizontal run.

6. In an apparatus for drying and shrinking textile fabric, a conveyor including successive basket loops of foraminous material movable through a horizontal run, said basket loops being of relatively narrow loop width and of substantially greater loop depth, means for driving said conveyor at a predetermined speed, means for feeding the fabric to the conveyor at one end of said run at a rate sufficiently greater than the speed of said conveyor that the fabric is loosely deposited in the basket loops with excess of the fabric at least approximately equal to the expected lengthwise shrinkage of the fabric, so that the fabric may shrink and still be supported by the basket loops, and means for impinging air on the top and bottom of the fabric to dry it as it is carried through said horizontal run.

7. In an apparatus for drying and shrinking textile fabric, an elongate housing, an endless conveyor extending longitudinally through said housing so as to provide a horizontal run of the conveyor through the housing to carry fabric

therethrough, said conveyor comprising an endless carrier and successive basket loops of foraminous material carried by said carrier, said basket loops being of relatively narrow loop width and of substantially greater loop depth, means for driving said conveyor at a predetermined speed, means for feeding the fabric to the conveyor at one end of said run at a rate sufficiently greater than the speed of said conveyor that the fabric is loosely deposited in the basket loops with excess of the fabric at least approximately equal to the expected lengthwise shrinkage of the fabric, so that the fabric may shrink and still be supported by the basket loops, and means for impinging air on the top and bottom of the fabric to dry it as it is carried through said horizontal run.

8. In an apparatus for drying and shrinking textile fabric, an elongate housing, an endless conveyor extending longitudinally through said housing so as to provide a horizontal run of the conveyor through the housing to carry fabric therethrough, said conveyor comprising an endless carrier and successive basket loops of foraminous material carried by said carrier, said basket loops being of relatively narrow loop width and of substantially greater loop depth, means for driving said conveyor at a predetermined speed, means for feeding the fabric to the conveyor at one end of said run at a rate sufficiently greater than the speed of said conveyor that the fabric is loosely deposited in the basket loops with excess of the fabric at least approximately equal to the expected lengthwise shrinkage of the fabric, so that the fabric may shrink and still be supported by the basket loops, longitudinally spaced air nozzles in said housing above and below said horizontal run of the conveyor for impinging air on the fabric as it is carried through the housing, said air nozzles extending substantially the full width of said

conveyor, and means for supplying heated air to said nozzles.

9. In an apparatus for drying and shrinking textile fabric, a conveyor including successive basket loops of foraminous material movable through a horizontal run, said basket loops being of relatively narrow loop width and of substantially greater loop depth, means for driving said conveyor at a predetermined speed, means for feeding the fabric to the conveyor at one end of said run at a rate sufficiently greater than the speed of said conveyor that the fabric is deposited in the basket loops with sufficient looseness of the fabric to permit shrinkage thereof without subjecting the fabric to undesirable

5
10
15

tension, and means for impinging air on the top and bottom of the fabric to dry it as it is carried through said horizontal run.
